(57) CLAIM

We claim the ornamental design for a bottle, as shown and described.

DESCRIPTION

FIG. 1 is a top/right/front perspective view of a bottle; FIG. 2 is a bottom/left/rear perspective view thereof; FIG. 3 is a front elevational view thereof, for which a rear elevational view would be a mirror image thereof; FIG. 4 is a left side elevational view thereof; FIG. 5 is a right side elevational view thereof; FIG. 6 is a top view thereof; and, FIG. 7 is a bottom view thereof.

The broken lines shown are included for the purpose of illustrating the unclaimed portions of the article and form no part of the claim.
